UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

TACKING AND BARRING MACHINE.

Application filed January 20, 1923. Serial No. 613,828.

To all whom it may concern:

Be it known that I, EDWARD B. ALLEN, a citizen of the United States, residing at Newtown, in the county of Fairfield and 5 State of Connecticut, have invented certain new and useful Improvements in Tacking and Barring Machines, of which the following is a specification, reference being had therein to the accompanying drawings.

10 This invention relates to that class of sewing machines used for tacking and barring. Such machines usually comprise stitch-forming mechanism, a work-clamp and a feed-cam and connections for relatively 15 moving the stitch-forming mechanism and work-clamp to position the stitches in the desired group formation. It is usual to provide two treadles for operating the machine; one of the treadles being connected 20 to open the work-clamp and the other to shift the stop-motion lever to running position. It is customary to use these machines for tacking the ends of pocket openings, for barring buttonholes and for reinforcing the 25 fabric in many other parts of garments where it is likely to tear.

The work of many prior machines of this class, particularly machines used for barring buttonholes, has been criticized because 30 of the tendency of the buttonhole slit to gape at the barred end. Attempts have been made in other machines to overcome this tendency by providing the machine with a work-clamp having means for contracting 35 it to full-in or compact the work toward the line of the buttonhole-slit prior to the barring operation. So far as I am aware, however, clamp-contracting devices heretofore 40 used have either required a comparatively complicated and expensive automatically 45 acting mechanism for their operation, or have required to be operated by a special movement of the operator's hand, thus slowing up production.

50 An object of the present invention is to provide a tacking and barring machine with clamp-contracting means of simple and inexpensive construction which may be operated without requiring special motions of the operator's hand.

55 A further object of the invention is to provide a machine of simple construction which will handle heavy work or will sew a "tack" or "bar" at a considerable distance 60 from the edge of the work.

To the attainment of the ends in view a work-clamp having an overhanging arm and deep throat is provided. At the free or forward end of the work-clamp are mounted a pair of laterally shiftable clamping feet. A 60 vertically sliding bar having oppositely inclined surfaces is preferably provided in the head at the end of the overhanging arm of the work-clamp for moving the feet together to full-in the work. This bar is connected 65 to be operated by movement of the stop-motion treadle in starting the machine, thus obviating the necessity of special motions on the part of the operator to contract the clamp and also obviating the necessity of 70 employing more complicated and costly automatic mechanism for contracting the clamp. Preferably, the sliding bar referred to is operated by means of a bellerank-lever 75 fulcrumed on the overhanging work-clamp arm and connected by a link to an extension of the usual treadle-operated lever of machines of this class which shifts the stop-motion lever to running position. The machine is also equipped with the usual treadle-controlled clamp-lifting mechanism which 80 raises the clamping feet for insertion and removal of work.

In the accompanying drawings, Fig. 1 is 85 a side elevation of a tacking and barring machine embodying the invention. Fig. 2 is a fragmentary reverse side elevation of the machine. Fig. 3 is a front elevation of the work-clamp with the clamping feet spread. Fig. 4 is a similar view with the 90 clamping feet contracted to compact the work. Fig. 5 is a horizontal section on the line 5—5, Fig. 3. Fig. 6 is a disassembled perspective view of the work-clamping elements and Fig. 7 is a plan view of a sample 95 of work done by the machine.

For the purposes of the present disclosure the invention is embodied in a machine of the well known Singer button sewer or Class 68 type represented, for example, in 100 the United States patents to Barron, No. 1,093,241, of April 14, 1914, and No. 1,194, 588, of Aug. 15, 1916. Machines of this type are commonly constructed with a bed 1, standard 2, overhanging bracket-arm 3 105 and head 4 in which is journaled the reciprocating needle-bar 5 carrying the needle 6 which cooperates with the usual loop-taker beneath the bed 1 to form stitches. The main driving shaft of the machine ear- 110

ries at its rear end the tight and loose pulleys 7 and 8 over which runs a belt controlled by the usual belt-shipper 9 carried by the stop-motion lever 10 fulcrumed at 11 and forming a part of the usual stop-motion device more fully represented in the first-mentioned Barron patent. Machines of this type also commonly embody a pattern cam or feed-wheel 12 having grooves 13 and 14 in its inner and outer faces, respectively. The inner groove 13 customarily actuates a suitable follower-lever 15 which through the usual connections imparts longitudinal motion to the work-clamp supporting bar 16. The outer groove 14 customarily actuates a suitable follower-lever 17 which, through the usual connections, imparts transverse components of motion to the work-clamp supporting bar 16.

20 The work-clamp may be and preferably is of the type having an overhanging arm in the form of a gooseneck affording a deep throat in order that the work may be stitched at a considerable distance from its edge. The lower work-clamp supporting bar 16 carries at its front end the usual lower work-clamping element or plate 18 and has mounted adjacent its rearward end the base 19 of the overhanging clamp-arm 20 terminating in a head 21 closely adjacent the head 4 of the sewing machine frame. The head 21 of the upper clamp-arm is formed in its front face with a deep vertical channel or slideway 22 for the vertical clamp-contracting bar 23 having at its lower end the laterally extended wings 24 formed with clamp-contracting inclined surfaces 25 and parallel holding surfaces 26, 26'.

40 The clamp-contracting and holding surfaces, 25 and 26, 26' are engaged by the roller pins 27 mounted on the shanks 28 of the upper work-clamping feet 29 which are notched at 30 to expose the section of the work to receive the tacking or barring stitches. The shanks 28 of the clamping feet are pivotally mounted on the parallel fulcrum pins 31 fixed to short transverse arms 32 projecting laterally from a second vertical slide-bar 33 parallel to the slide-bar 23 and guided in the slideway 34 in the head 21. Cross-bars 35 are screwed to the head 21 to retain the slide-bars 23 and 33 in their respective ways and the head 21 is cut away at 36, 36, Fig. 6, intermediate the cross-bars 35 to afford clearance for the short transverse arms 32, 32, of the slide 33 in its up-and-down movements.

60 A U-shaped leaf-spring 37 is formed with an eye at its bend through which passes a screw 38 securing such spring to the slide-bar 33. The legs of the spring bear outwardly against the shanks 28 of the clamping feet to retain the roller-pins 27 in contact with the operative surfaces 25 and 26,

26' of the clamp contracting slide-bar 23. A forwardly projecting pin 39 is mounted on the slide-bar 33 in a position to extend over the usual horizontal clamp-lifting arm 40 carried at the lower end of the clamp-lifting bar 41 which is mounted in the head 4 parallel to the needle-bar 5 and at its upper end is connected to be operated by the usual treadle-controlled clamp-lifting lever 42. One of the lateral arms 32 of the slide-bar 33 is formed with an upward extension 43 which is yieldingly pressed downwardly, to hold the feet 29 in clamping engagement with the work, by means of a relatively strong leaf-spring 44 bearing at its rear end upon the stud-screw 45. The pressure of the spring 44 may be adjusted by turning the screw 46 which bears upon the spring 44 between the ends of the latter. The slide-bar 33 also preferably has secured to its lower end a gauge member 47 having at its lower end a very thin fin 48 terminating at its front end close to the sewing point but not within the range of action of the needle. The fin 48 has a lower horizontal edge 90 which is disposed slightly below the plane of the lower oppositely serrated surfaces 49, Fig. 3, of the clamping feet so as to slightly enter a buttonhole or other slit in the work and assist the operator in properly positioning and alining the work.

The clamp-contracting slide-bar 23 is recessed at its upper end at 50 to admit the lateral pin 51 fixed to the horizontal arm 52 of a bellcrank-lever fulcrumed at 53 to a bracket 53' fixed to the overhanging clamp-arm 20. The downwardly extending arm 54 of the bellcrank-lever is loosely entered by the forward end of a link or push-rod 55 having a collar 56 fixed thereto adjacent the arm 54. A relatively weak coil spring 57 is secured at one end to the arm 54 and at its opposite end to the bracket 58 which supports the usual clamp-shifting levers 15 and 17. This spring tends to return the bellcrank-lever and clamp-contracting slide-bar to the position shown in Figs. 1, 2 and 3.

At its rearward end the rod or link 55 loosely enters an aperture in an arm 59 which is extended laterally and downwardly from the usual treadle operated bell-crank-lever 60 which presses at 61 against the stop-motion lever 10 to shift the latter to dotted line or running position, Fig. 1. A pair of collars 62 are fixed to the rod 55 on opposite sides of the arm 59. 115 120

When the operator depresses the clamp-lifting treadle, the lever 42 is rocked to elevate the slide-bar 41 which, in turn, lifts the slide-bar 33 and upper clamping-feet 29 against the pressure of the strong leaf spring 44. As soon as the feet 29 are lifted clear of the work they are separated or spread by the spring 37 preparatory to engaging a new piece of work in their separation. 125

rated positions, Fig. 3. After the work has been located in the work-clamp, with the feet 29 in spread position, Fig. 3, the operator depresses the stop-motion operating treadle 5 and thereby rocks the bellcrank-lever 60 to shift the stop-motion lever 10 to dotted line or running position, Fig. 1. This motion of the lever 60 imparts a forward impulse to the link or push-rod 55 which rocks the bellcrank-lever 52, 54 and thus lifts the clamp-contracting slide-bar 23 to carry its oppositely inclined surfaces 25 into engagement with the roller-pins 27 and shift the latter inwardly to relatively approach the 15 clamping feet 29 and thereby compact or full-in the work or, in buttonhole finishing, crowd the edges of the buttonhole close together so that they will not gape after the bar has been sewed.

20 The distance between the parallel holding surfaces 26' is such that they press rather tightly against the roller-pins 27 and cause the slide-bar 23 to remain in elevated position, as shown in Fig. 4, during the sewing 25 operation; the spring 57 being too weak to overcome the frictional resistance of the surfaces 26' and roller-pins 27.

When the sewing is completed and the operator elevates the slide-bar 33, to remove 30 the work, the roller-pins 27 are forcibly carried above the holding surfaces 26' thereupon relieving the friction between such pins and surfaces and permitting the bar 23 to drop to the position shown in Fig. 3 under 35 the influence of the spring 57.

When the machine is used say for barring buttonholes, the edges of the slit *b* are pressed tightly together by the relative approach of the feet 29 and the needle lays a 40 series of long stitches *a* back and forth across the end of the slit *b*. The needle then lays a series of short stitches *c* in zigzag arrangement covering the long stitches *a* and binding down the gimp *d* and the ends of the 45 overseaming threads *e*. When the work is removed from the machine the slit *b* will not gape and the work presents a neatly finished appearance.

Having thus set forth the nature of the 50 invention, what I claim herein is—

1. A tacking and barring machine having, in combination, stitch-forming mechanism, a stop-motion device, manually operated means for throwing the stop-motion device 55 to running position, a contractible work-clamp adapted to full in the work adjacent the sewing point, and means connected to be operated by the manually operated means for throwing the stop-motion device to running position, for contracting the work-clamp prior to sewing.

2. A tacking and barring machine having, in combination, stitch-forming mechanism, a stop-motion device for controlling its period 60 of action, manually operated means for oper-

ating the stop-motion device to start the machine, a work-clamp having clamping elements which are relatively movable laterally while in engagement with the work to compact the latter, means for relatively 70 moving the stitch-forming mechanism and work-clamp to sew a group of stitches, means for opening the work-clamp for removal and insertion of work, and means connected to be operated by the manually controlled 75 stop-motion operating means, for relatively approaching the clamping elements to compact the work prior to sewing.

3. In a tacking and barring machine, stitch-forming mechanism, a work-clamp, a lever mounted on said work-clamp and connections for contracting the clamp to full-in the work, a feed-wheel and connections for moving the work-clamp to position the 80 stitches, a stop-motion device for controlling the period of operation of the stitch-forming mechanism, manually operated means for throwing said stop-motion device to running position, and a connection between said means and said lever for operating the clamp-contracting connections.

4. In a sewing machine work-clamp, a lower clamp-element, an upper clamp-arm in the form of a gooseneck rigidly associated with said lower clamp-element, relatively movable clamping feet carried by 95 said gooseneck at the free end of the latter and means for relatively approaching said clamping feet to compact the work.

5. In a sewing machine work-clamp, a 100 lower clamp-supporting bar, a lower clamp-plate carried at one end of said bar, an upper clamp-arm in the form of a gooseneck rigidly mounted adjacent the other end of said lower bar, said gooseneck terminating in a head, a slide-bar mounted in said head, laterally movable clamping feet carried by said slide-bar, and means for lifting and lowering said slide-bar and for relatively approaching said clamping feet 105 while in engagement with the work.

6. In a sewing machine work-clamp, a lower clamp-element, an upper clamp-arm overhanging said lower clamp-element and defining therewith a work-receiving throat, 115 a slide-bar mounted on said upper clamp-arm, clamping feet pivotally carried by said slide-bar, means for moving said slide-bar to open and close the clamp, and means for relatively approaching said clamping feet 120 about their pivots while in engagement with the work to compact the latter.

7. In a sewing machine work-clamp, a lower clamp-plate, upper clamping feet, a carrier on which said clamping feet are pivoted for movement toward and away from each other, an arm rigidly associated with and overhanging said lower clamp-plate, said carrier being movably carried 125 at the free end of said arm and adapted 130

to shift the clamping feet toward and away from the lower clamp-plate, means for moving said carrier to open and close the work-clamp, and means carried by said arm and 5 movable independently of said last-mentioned means for relatively approaching the clamping feet while in engagement with the work to full in the latter.

8. In a sewing machine work clamp, a 10 lower clamp-plate, an arm overhanging and rigidly associated with said clamp-plate, a carrier mounted on said arm for movement

toward and away from the lower clamp-plate, upper clamping members mounted on said carrier for work fulling movements, and a clamp contractor movably carried by 15 said arm and having oppositely inclined surfaces adapted to engage said upper clamping members to move them toward each other while in engagement with the 20 work.

In testimony whereof, I have signed my name to this specification.

EDWARD B. ALLEN.
